(57) **CLAIM**

The ornamental design for a cable management bag, as shown and described.

DESCRIPTION

FIG. 1 is a front view of a first embodiment of the cable management bag;

FIG. 2 is a side view of thereof, the right and left side views being mirror images;

FIG. 3 is a top view thereof;

FIG. 4 is a perspective view thereof shown in a condition of use;

FIG. 5 is a perspective view thereof shown in another condition of use;

FIG. 6 is a front view of a second embodiment of the cable management bag;

FIG. 7 is a perspective view thereof shown in a condition of use;

FIG. 8 is a front view of a third embodiment of the cable management bag;

FIG. 9 is a perspective view thereof shown in a condition of use;

FIG. 10 is a front view of a fourth embodiment of the cable management bag;

FIG. 11 is a perspective view thereof shown in a condition of use;

FIG. 12 is a front view of a fifth embodiment of the cable management bag;

FIG. 13 is a side view thereof, the right and left side views being mirror images; and,

FIG. 14 is a top view thereof.

The broken lines in the figures illustrate environment and form no part of the claimed design.
